HAIR CURLER

Joseph H. Paul, Providence, R. I.

Application January 19, 1949, Serial No. 71,593

1 Claim. (Cl. 132—41)

1

My present invention relates to hair curlers, and more particularly to a curler for producing a flat curl.

The principal object of the present invention is to provide a hair curler which will permit the user to flatten the curl close to the head.

Another object of the present invention is to provide a hair curler similar to the conventional types of curlers and which can be manipulated to flatten the curl to the head.

A further object of the present invention is to provide a curler for home use, easy and economical to manufacture and assemble, for making a flat curl.

With the above and other objects and advantageous features in view, my invention consists of a novel arrangement of parts, more fully disclosed in the detailed description following, in conjunction with the accompanying drawings, and more particularly defined in the appended claim.

Referring to the drawings—

Fig. 1 is a perspective view of a hair curler embodying my invention;

Fig. 2 is a perspective view showing a curl formed on the curler;

Fig. 3 is a similar view showing the curler flattened to flatten the curl;

Fig. 4 is an enlarged section showing one end of the curler in raised position; and

Fig. 5 is a similar view in collapsed position.

The conventional type of hair curler for home use comprises a cylinder for winding the hair around, a means for locking the curler in place, and some method of removing the curler after the curl has set. However, if the woman wishes a curl flattened to the head, it is necessary to visit a hairdresser as heretofore there was no curler made which would make a flattened curl.

The present invention is designed to permit a flattened type curl to be made at home by conventional methods. This is accomplished by providing a curler which collapses to permit the curls to flatten towards the head and remains in this position until the hair is set.

Referring more in detail to the drawings illustrating my invention, the curler shown in Fig. 1 comprises spaced parallel body portions 10 and 11 slightly arcuate in cross section and provided with perforations 12 for air circulation to dry the hair. The portions 10 and 11 are held in spaced parallel relation by rectangular wire loops 13 and 14 positioned at each end to form a rectangular frame. As shown in Figs. 1 and 4, each

2

end of the body portions 10 and 11 is turned around one side of the wire loop to frictionally engage the wire. The amount of frictional engagement is such that the parts will tend to remain in position, but can be readily pushed laterally into the rhomboid shown in Fig. 3.

One end of the portion 10 is cut away, permitting a tongue 15 to be loosely pivotally mounted on the loop 13. The tongue 15 supports an integral auxiliary portion 16 which is arcuate in shape and perforated and is designed to loosely fold over the portion 10. A locking member 17 is hinged to the curler and comprises spaced parallel wires 18 and 19, one end of the wire 18 being pivotally attached to the portion 10 adjacent one end, and one end of the wire 19 being pivotally attached to the portion 11 adjacent one end. The free ends of the wires 18 and 19 are connected by a wire 20, the ends of the wires being loosely bent around each other to permit free movement.

In use, the curler is pushed into the position shown in Fig. 1, the lock frame 17 being swung completely out of the way. The hair ends are placed over the portion 10 and the auxiliary portion 16 is swung down over the hair. The curler is now turned in the conventional manner so that a full curl forms on the curler as shown in Fig. 2. In this position the curl will retain the auxiliary portion tightly over the portion 10 and lock the hair ends and curl in place. The lock frame 17 is now pivoted over the curler until the wire 20 passes over the end as shown in Fig. 2. The curler is now locked and the curl cannot unwind. Side pressure on the curler will force it into the rhomboid position shown in Fig. 3, the portions 10 and 11 collapsing toward each other laterally so that the curl is flattened out as shown in Fig. 3 and in the dotted lines in Figs. 4 and 5. The curl is allowed to dry and then the frame 17 is swung into open position and the curler slipped out in the conventional manner.

The above construction thus provides a simple method of forming a curl, flattening it against the head by collapsing the curler, and allowing it to dry and retain its flattened shape. The construction is simple and the operation is similar to that of the conventional curler.

Besides the flattened curls, the present curler permits the forming of waves. The flattened curls tend to blend into each other, and when brushed a continuous wave is formed similar to a professional sculptured curl.

While I have described a specific embodiment of my invention, it is obvious that changes may

readily be made in the size, shape, and relative arrangement of parts, without departing from the spirit and scope of the invention as defined in the appended claim.

I claim:

A hair curler for producing a flat hair curl which lies closely against the head, said curler comprising a pair of parallel bars, links pivotally securing the opposite ends of each bar whereby said bars are retained in spaced relationship to each other forming a rectangular shaped curler which is deformable to a rhomboidal shape when said curler is collapsed, an auxiliary member carried by said curler for clamping a portion of a strand of hair to be curled against one of said bars to hold the same in position for winding about said spaced parallel bars, and means mounted on said curler for locking the hair

strand curled about said bars to secure the same thereto and prevent unwinding of the hair strand therefrom.

JOSEPH H. PAUL.
